UNITED STATES PATENT OFFICE.

SYDNEY CURNOW VOSPER, OF PETERSFIELD, ENGLAND.

ARTIST'S EASEL.

1,072,534.

Specification of Letters Patent. Patented Sept. 9, 1913.

Application filed September 12, 1912. Serial No. 720,052.

To all whom it may concern:

Be it known that I, SYDNEY CURNOW VOSPER, a citizen of the United Kingdom of Great Britain and Ireland, and resident of The Holt, Petersfield, Hampshire, England, have invented certain new and useful Improvements in Artists' Easels, of which the following is a specification, such as will enable others skilled in the art to which it appertains to make and use the same.

This invention relates to easels such as are used by artists and are cruciform, the cross bar being capable of a sliding movement on the main bar for the purpose of accommodating sketching blocks and the like of different sizes, the lower edge of the said blocks resting against the cross bar while the upper edge is held on a notched support movable on the main bar. The invention concerns particularly the method of mounting this support upon the bar.

In the accompanying drawings, Figure 1 shows the whole easel, and Fig. 2 an enlarged view of a form of the present invention, the bar to which it is applied being shown by dotted lines.

In these drawings the notched support *a* is furnished with a slot *b* and stop *c*. A screw *d* is passed through sliding bracket *e* and through the slot *b* so that the angle of the support can be regulated at will in relation to the bar *h* and fixed where required by tightening the screw *d*. The bracket which comprises the two side members is adjusted 30 on the bar *h* by bolt and nut *f* in slot *g* which will when loosened permit the bracket to slide on the said bar. When not in use the bolt *d* is loosened and the support folded down upon the bar. Stop *c* prevents the

support leaning too far back if under much pressure.

What I claim and desire to secure by Letters Patent is:—

1. An easel comprising a main bar having a longitudinal slot, a cross bar adjustable on said main bar, a notched support on said main bar, one end of said support extending through said longitudinal slot, means for adjusting the support, a stop on one end of the support, said stop having curved edges, the curved edges of said stop adapted to engage the under side of the main bar and restrict the movement of said support.

2. An easel comprising a main bar having a longitudinal slot, a notched support on the main bar, means on the bar for adjustably supporting the notched support, said notched support having an offset portion, an enlargement on one end of the notched support, said enlargement adapted to engage the under side of the main bar for limiting the movement of the support.

3. An easel comprising a main bar having a longitudinal slot, a notched support operating in the slot, an adjustable bracket supporting the notched support, said bracket comprising side members, means for holding the bracket in various positions of adjustment, and means for forcing the side members together for clamping the notched support.

In witness whereof I have hereunto set my hand in presence of two witnesses.

SYDNEY CURNOW VOSPER.
